UNITED STATES PATENT OFFICE.

HENRY O. ENGSTROM, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed June 11, 1924. Serial No. 718,393.

My invention relates to electric switches, and particularly to switches of the push-through type. The object of my invention is to provide a simple and inexpensive switch mechanism which may be readily manufactured and assembled, and is efficient in service.

In the accompanying drawings—

Fig. 1 is a vertical section through an electric fitting in which a switch embodying my invention in one form is shown;

Fig. 2 is a section on the line 2—2, Fig. 1;

Fig. 3 is a section on the line 3—3, Fig. 1; and

Fig. 4 is an end view of a lamp socket in which the switch is here shown installed.

While I have shown my invention embodied in a lamp socket, it will be understood that the switch mechanism, to which my invention particularly relates, may be used in any appropriate type of fitting, and its utility is not confined to lamp sockets. The lamp socket installation illustrates merely an appropriate use of the switch.

The socket shown comprises a usual metallic casing shell 15, with separable cap 16, both lined with insulation 17 and constituting a housing for the socket body and its associated parts. In its general features the socket body resembles that illustrated in the copending application of Carl Eric Anderson, Ser. No. 713,277, filed May 14, 1924, and comprises a porcelain button 18 and an associated washer 19 arranged at one end of the button, the latter supporting the screw shell lamp terminal 20 and center contact 21, and both of the wire terminals 22 and 23. The wire terminal 22 is directly connected to the screw shell terminal 20, while the wire terminal 23 is provided with an offset flange 24 which projects into the switch chamber 25 and constitutes one of the switch contacts. The base flange of the cooperating switch contact 26 is engaged by the rivet 27 which holds the center contact 21 to the outer face of the disc 19. The circuit is thus made and broken on the center contact of the socket.

The switch mechanism comprises a rectilinearly movable push plate 28 having at its opposite ends push buttons 29 which project through suitable guide openings 30 in the insulating lining and shell 15 of the casing. The push plate passes through the

switch chamber 25 intermediate the contacts 24 and 26 and is guided in slots 31 and 32 (Fig. 3) which extend between the switch chamber and the bays 33 and 34 which accommodate the inner ends of the push buttons 29. The push plate is formed from sheet metal, and is provided intermediate its ends with a peaked cam 35, the inclines of which terminate in legs 36 and 37, the engagement of which in the guide slots 31 and 32 prevents lateral play, while their length is sufficient to prevent longitudinal tilting of the plate by reason of its engagement between the disc 19 and the bottoms of the guide slots 31 and 32 in the button 18.

Riding the cam 35 is the switch piece 38. The latter is also struck from sheet metal, and its head is of sufficient transverse extent to bridge the contacts 24 and 26, as shown in Figs. 2 and 3. The shank 39 projecting from the head of the switch piece passes to the side of the push plate 28 and extends toward a well 40 formed in the button 18 and opening to the switch chamber 25. A foot piece 41 is offset from the leg 39 across the push plate 28 and is apertured to receive one end of a pull coil spring 42. The opposite end of the latter engages a depressed broad web 43 between the ends of a narrow bearing plate 44, which lines the bottoms of the slots 31 and 32, and against which the lower ends of the legs 36 and 37 of the push plate are held in bearing engagement by the spring 42. A notch 45 in the lower margin of the head 38 of the switch piece, accommodates the peaked cam 35 of the push bar, and the engagement of the switch plate therewith is constantly maintained by the stress of the pull spring 42. The push plate 28, bearing plate 44, switch piece 38 and spring 42 thus form an assembly unit, self-contained and self-maintained by the stress of the spring.

The operation of the mechanism is readily understood. In Figs. 1, 2 and 3 the switch is shown in circuit-closing position, that is to say with the switch piece 38 bridging the contacts 24 and 26. If the push plate be shifted to the left, the switch piece 38 (retained against movement therewith by its engagement with the contacts 24 and 26) is forced to ride up the incline *a* of the cam 35, thus wiping the engaged surfaces of the contacts and further stressing the spring 42.

As the peak of the cam 35 passes the switch piece 38, the spring 42 causes the latter to run down the opposite incline *b* of the cam, and thus move rapidly across the switch chamber 25, against the opposite wall of which it is halted in open-circuit position. During the transverse shifting of the push plate, its legs ride the bearing plate 44, which is thus held against displacement under the increased stress of the spring 42. Longitudinal displacement of the plate 44 is prevented by the engagement of its depressed web 43 in the well 40. It will thus be observed that the bearing plate which forms the element to which one end of the spring is anchored, is held in position by the push plate which tensions the spring, while at the same time it affords a good bearing surface for the ends of the webs 36 and 37, and obviates the necessity for finishing the surface of the porcelain at the bottoms of the slots 31 and 32 upon which the legs of the push plate would otherwise bear with considerable friction. A smooth operation of the push plate is provided and at the same time a simple and secure anchorage for the fixed end of the spring 42.

To assemble the parts it is only necessary to pass the push bar assembly unit into the switch chamber and guide slots of the button 18 until they bottom therein. The disc 19, with the conductors assembled thereon, may then be mounted at the end of the button and the parts secured together by the two holding bolts 46 which pass through the button 18 and disc 19 and engage, respectively, the nut 47 and the tail 48 of the wire terminal 22, which overlies the base flange 49 of the screw shell contact 20. The assembly operation is thus exceedingly simple and expeditious, while the mechanism is efficient and unlikely to become deranged.

Various modifications in details of construction will readily occur to those skilled in the art which do not depart from what I claim as my invention.

I claim—

1. An electric switch comprising an insulating body recessed to afford a switch chamber with guideway opening thereto, a rectilinearly movable actuator accommodated in said guideway and movable across said switch chamber, said actuator comprising a peaked cam, a switch piece movable across the switch chamber and riding said cam, a spring anchor to which one end of said spring is attached, and a sliding engagement between said anchor and the actuator serving to hold said anchor against displacement under the stress of the spring.

2. In an electric switch, an assembly unit comprising a rectilinearly movable actuator with peaked cam, a switch piece riding said cam, a bearing plate and a switch operating spring interposed between said bearing plate and switch piece and serving to hold the parts in self-contained assembled relation.

3. In an electric switch, an insulating body recessed to afford a switch chamber, a well and a guideway opening thereto, a rectilinearly movable peaked cam actuator traversing the chamber and guideway, a switch piece riding the actuator cam, a combined spring anchor and guideway lining, having a portion offset into said well, and a spring engaging said offset portion of the lining member and extending between the switch piece and anchor and serving to hold the actuator against the guideway lining.

In testimony whereof I have signed my name to this specification.

HENRY O. ENGSTROM.
